(57) **CLAIM**

The ornamental design for a bead spinner set, as shown and described.

DESCRIPTION

FIG. 1 is a perspective view of a bead spinner set showing my new design;

FIG. 2 is a perspective view of a first component of a bead spinner set, shown separately for ease of illustration;

FIG. 3 is another perspective view thereof;

FIG. 4 is another perspective view thereof;

FIG. 5 is a front elevational view thereof;

FIG. 6 is a rear elevational view thereof;

FIG. 7 is a left side elevational view thereof;

FIG. 8 is a right side elevational view thereof;

FIG. 9 is a top plan view thereof;

FIG. 10 is a bottom plan view thereof;

FIG. 11 is a perspective view of the first component of the bead spinner set where the first component of the bead spinner set is in a configuration of use;

FIG. 12 is a cross-sectional view taken along the line 12-12 shown in FIG. 5;

FIG. 13 is a perspective view of a second component of a bead spinner set, shown separately for ease of illustration;

FIG. 14 is another perspective view thereof;

FIG. 15 is another perspective view thereof;

FIG. 16 is a front elevational view thereof;

FIG. 17 is a rear elevational view thereof;

FIG. 18 is a left side elevational view thereof;

FIG. 19 is a right side elevational view thereof;

FIG. 20 is a top plan view thereof;

FIG. 21 is a bottom plan view thereof; and,

FIG. 22 is a cross-sectional view taken along the line 22-22 shown in FIG. 16.

The broken lines immediately adjacent to the shaded areas depict the bounds of the claimed design, while all other broken lines in FIG. 1 are directed to environment. The dash-dot broken lines form no part of the claimed design.

1 Claim, 22 Drawing Sheets
